REVERSIBLE WINDOW

Leroy B. Taylor, Cleveland, Ohio

Application May 8, 1934, Serial No. 724,521

5 Claims. (Cl. 189—67)

My invention relates to reversible windows and in particular to an improvement over my previous Patent No. 1,767,022, in that I am simplifying the pivoting means and also incorporate a means 5 for locking the sashes as an integral part of the reversible windows.

One object of the invention is to permit its application to a steel sash with new means of locking the same.

10 Another object is to provide an improved pivoting means. Other objects will be evident from the following specification and its accompanying illustrations, in which:—

Fig. 1 is a front plan view of the invention.

15 Fig. 2 is a sectional view taken on lines 2—2 of Fig. 1 but showing one window open.

Fig. 3 is an enlarged sectional view taken on lines 3—3 of Fig. 1 showing the sash locked in position.

20 Fig. 4 is similar to Fig. 3 but having the lock shifted to opening position.

Fig. 5 is an enlarged section taken on lines 5—5 of Fig. 1.

25 Fig. 6 is an enlarged fragmentary section of the lower sash.

Fig. 7 is an enlarged fragmentary sectional view of a locking chain device for locking the lower sash with the upper sash.

30 Fig. 8 is a fragmentary sectional view of the pivoting means.

Referring to the drawings; a window casing consisting of a head 10, jambs 11 and sill 12 is made to fit in an opening in the wall of a building, and a metal flange 13 formed on each jamb 35 11 produces a channel which extends the full length of the frame or casing between the head 10 and the sill 12.

An upper sash 14 comprising an inner angle 15, glass 16 and outer angle 17, and a lower sash 40 18 comprising an inner angle 19, glass 20 and outer angle 21, are pivotally movable within the frame or casing by means of long lever arms 22 and 22a and short lever arms 23 and 23a. Said long lever arms are pivotally attached near the 45 lower end to the jamb 11 by screws 24 in such manner as to allow a free swinging movement of said arms; and the angular ends 25 of arms 22 and 22a act as a stop when the sash 14 or 18 is swung open, the ends 25 pressing against the channel 13. The short lever arms 23 and 23a have a lug 26 which forces the long lever arms 22 and 22a back to a perpendicular position when the sash 14 and 18 are closed. Short lever arms 23 and 23a are pivoted at 27 to long lever arms 22 55 and 22a, the opposite end of said short levers

form angular portions 28 and 28a which are pivotally attached to outer angles 17 and 21 respectively, by pivot pins 29. Thus where the sash are opened or reversed they swing inwardly as shown by the lower sash in Fig. 2.

5 A pivot block 30 is split at 31 and has an aperture 32 in which a pivot pin 33 is inserted, said pivot pin having a flange 34 which is used as a thrust bearing between the block 30 and sash 14 or 18 to which the pivot pin 33 is attached. A tapered bolt 35 is screwed into the threaded top 36 of the block 30 to insure the proper amount of pressure of the block 30 against the sides of the channel 13.

10 A lock comprising a box 37 with apertures 38 and 39 in the front and bottom walls respectively is provided with a sliding catch 40 with a spring bolt 41 fixed thereto and extending through aperture 42 in the top of said box 37.

15 A spring 43 is coiled around the said bolt 41 between the top of catch 40 and a washer 44 on the inside of said box. The catch 40 has a rounded end 45 under which a finger 46 of finger pull 47 is mounted. Said finger 46 projects into the box through the aperture 38, the finger pull 25 47 being pivotally mounted between projecting ears 48 of plate 50 by means of a pivot pin 51.

20 A second finger pull 52 with a split flange projection 53 is mounted over the projecting outer angle 17 of sash 14 and attached rigidly thereto, 30 thus as finger pull 47 is drawn down, finger 46 lifts the rounded end 45 of the tongue 40, compressing spring 43, and finger pull 52 can then be pulled inwardly thus opening the sash.

Attached to outer angles 17 by bolts 53 is a 35 tapered channel 54 which presses into groove 55 in the head 10, when the sash is closed, and a slot 49 allows a slight movement of the channels 54 and 62 to ensure a tighter fit in the grooves 55 and 64. A similar channel 62 with bolt 63 is also 40 mounted on each side of the sash 14 and 18 and attached to the outer angles 17 and 21 and wedge into grooves 64 in jambs 11 as shown in Fig. 5. These channels thus used form a weather stripping and seal the windows against inclement 45 weather.

55 A chain catch comprises an angle 56 attached to outer angle 21 of sash 18 and a slotted housing 57 mounted on outer angle 17 and inner angle 15 of sash 14, a chain 58 attached to said angle 50 56 at one end and having a flanged anchor 59 attached at its other end, said anchor being slipped in or out of the slotted housing 57 as desired for locking or unlocking the sash. A spring clip 60 attached to the outer angle 17 of 55

the sash 14 and bearing against the flanged edge 61 of the outer angle 21 of sash 18 retain the sash 14 and 18 in a closed position, the flanged edge 61 of outer angle 21 forming a seal against 5 the weather.

By lifting the latch 40 by means of the lever 47 the upper sash may be swung open, and reversed for cleaning if desired. Also by releasing the chain catch the lower sash may be similarly 10 opened. In either case, the blocks 30 slide up in the channel 13 and the sash turn on the pivots 33, and are held in position by the levers 22, and 23, and 22a and 23a, respectively, the swing of 15 the long levers 22, 22a being stopped by the contact of the faces 25 with the flange 13.

I claim:

1. The combination with a window frame and reversible sash, of a pair of levers connected at one end to the sash and pivoted at the other end 20 to the frame, the last mentioned end projecting beyond the pivot to stop against the frame when 25 swung to a certain position.

2. The combination stated in claim 1, the frame having a flange against which said end stops.

3. The combination with a frame having a channel extending along each jamb, of a reversible sash in the frame, split blocks sliding in the channels and pivoted to the sash, and adjustable means to expand the blocks to adjust 5 their fit in the channels.

4. The combination stated in claim 3, said 10 means comprising a tapered screw fitting in the split.

5. The combination of a metal window frame the jambs of which have a flange forming channels, a metal sash reversible in the frame, blocks 15 pivoted to the sash and slidable in the channels, and jointed arms pivoted to the sash and to the frame and arranged to stop against said flange in either open or closed position of the sash.

20 LEROY B. TAYLOR.
